[57] **CLAIM**

The ornamental design for a finger food attachment tray for a saucer, as shown and described.

DESCRIPTION

FIG. 1 is a side elevational view of a finger food attachment tray for a saucer showing my new design;

FIG. 2 is a top plan thereof;

FIG. 3 is a bottom plan thereof;

FIG. 4 is an elevational view on an enlarged scale as seen from the right of FIG. 1;

FIG. 5 is an elevational view on an enlarged scale as seen from the left of FIG. 1;

FIG. 6 is a top plan view on an enlarged scale of a modification of the design of FIGS. 1 to 5;

FIG. 7 is a top perspective view of the design of FIGS. 1-5;

FIG. 8 is a bottom perspective view thereof;

FIG. 9 is a top perspective view of the design of FIG. 6; and

FIG. 10 is a bottom perspective view thereof.

FIG. 1**FIG. 2****FIG. 3**

FIG. 4.

FIG. 5.

FIG. 6.
